UNITED STATES PATENT OFFICE.

SAMUEL LAZARUS, OF CLEVELAND, OHIO.

ENGINE-TROUBLE DETECTOR.

1,254,416.

Specification of Letters Patent Patented Jan. 22, 1918.

Application filed October 18, 1915. Serial No. 56,510.

To all whom it may concern:

Be it known that I, SAMUEL LAZARUS, a citizen of the United States, residing at Cleveland, in the county of Cuyahoga and State of Ohio, have invented certain new and useful Improvements in Engine-Trouble Detectors, of which the following is a specification.

My invention relates to a trouble detector for internal combustion engines, and the invention comprises a simplified structure adapted to be conveniently connected and operated for the instant detection of ignition troubles in such engines, substantially as shown and described and particularly pointed out in the claims.

In the accompanying drawings, Figure 1 is a front view of the detector. Fig. 2 is a vertical central sectional elevation thereof, front to rear. Fig. 3 is a rear elevation complete and as otherwise seen in Fig. 2. Fig. 4 is a diagrammatic view showing the graduated electrical wires extending from the detector to facilitate convenient and correct connection with the respective engines.

The device thus shown is a complete article of manufacture and sale, adapted to be placed on any automobile having an engine embodying two or more cylinders. The present construction is particularly adapted for use with an engine having six or a less number of cylinders.

The desirability of a device of this kind and its practical utility need hardly be elaborated upon in the present advanced state of the automobile art, but it is well known that there is constant danger of trouble arising in multiple cylinder machines by reason of defective spark plugs or the like and in locating such trouble and without some such device as the present invention, it has always been necessary to make a systematic examination over possibly every cylinder in the series to locate the defect, whereas by my invention the trouble is instantly and definitely located and disclosed and without leaving the seat.

To these several ends I provide a simple form of detector comprising a relatively small casing *c* which is adapted to be secured to the dash of a machine and has a

dial face with a series of window openings *o* in a circle and corresponding numerals from 1 to 6 in a circle about the center of the dial opposite said openings and serving as numbers for the same. The said numbers run consecutively like the hours on a clock, and indicate the corresponding cylinders, which are numbered in like manner. A transparent or glass disk *d* is arranged inside over the said openings or windows *o* through which the driver is enabled to read the results ascertained by the indicating hand or spark-producing finger *f*. The said finger has an arbor or stem *a* slidably and rotatably mounted in casing *c* and is adapted to be depressed or pressed inward and rotated by grasping the insulate head *h* thereon. Operation is by said head, and spiral spring *s* sleeved upon said arbor outside the casing *c* serves to retract and hold the said finger out of possible contact with the several projecting wire terminals or contacts *g*. Each of the wires 1, 2, 3, 4, 5 and 6 has a corresponding terminal lug or projection *g* on the inner insulating disk *D* resting against a shoulder of the said casing and which disk is confined therein by sealing wax *w* or like composition behind the same and in which the several wires 1 to 6 with their insulation are more or less embedded at their connecting ends.

Normally, the current follows its usual channels, as between the magneto *M* and the respective spark plugs for the cylinders of engine *E*, but at the time of detection for defective plug or connection or other trouble at the engine the projections or terminals *g* are brought into a short circuit by finger *f* and the circuit is to ground or to the frame of the machine by the wire 7 which is connected with the ring 8 engaged with casing *c*, see Fig. 3.

To prevent possible confusion in connecting the several wires with the engines or of tags or marks thereon becoming lost or confused, I have graduated the lengths of the said wires serially, making No. 1 shortest and No. 7 longest, so that after connecting the wires 1 to 6 successively with the engines numbered in like manner the wire No. 7 remains to make the ground connection. Thus

also in making the said connections the work is simplified as the obvious steps to be taken. After fastening the dial to the dash, is to connect the shortest wire 1 to the spark plug 5 P of the first cylinder nearest the device where located on the dashboard or cowl of the machine. The next length of wire is attached to cylinder No. 2, and so on. For 10 four cylinder engines, wires Nos. 5 and 6 can be cut off close to dial or left unconnected to cut out the contacts *g* indicated by Nos. 5 and 6 on the face of dial.

When irregularities in the operation of the engine develop the source of trouble can 15 be detected instantly by pressing the spark-producing finger *f* inward and turning it to either the left or to the right in near or actual contact with the projections *g*. No spark or a weak spark indicates at once the 20 cylinder causing the trouble, possibly due to broken insulation, or carbon and oil deposits around electrodes, or the electrodes may be jammed or too far apart, or wire leading to that particular cylinder may be 25 broken or disconnected.

Where a spark appears intermittently or does not prove as strong as that secured from the other contacts, the cause of the trouble indicates a loose wire connection, 30 loose battery terminal, or improper connections at the distributing contacts and brushes of the magneto.

Where an intermittent spark develops in the detector when the engine is running on 35 the magneto, the operator should switch to battery and then operate the detector. Then if a normal spark in the detector is obtained it is obvious that the original trouble resides in the brushes or contact points of 40 the magneto, which should be cleaned, or in a loose terminal connection at the spark plug or battery. On the other hand, should all contacts give forth a good spark and motor still develop a miss, it is almost certain 45 that the trouble is in lack of compression due to carbon deposits on valve seat, leaky gaskets, impaired flow of gasoline to carburetor, or kindred causes. The device is also useful in locating loose operating parts and 50 knocking or rattling in the engine. That is, by pressing the finger *f* in contact with each projection *g* in succession to short-circuit each spark-plug in turn and in this way prevent explosions from occurring in selected 55 cylinders, it is possible to locate the noise and trouble. If the knock resembles a dull thumping as of one rock on another, it is pretty certain to be found in a loose wrist pin. If a sharp metallic knock, the trouble 60 can be traced to the connecting rod or main bearing, and a squeaking sound indicates a dry bearing and very prompt attention should be given to lubrication. A whistling sound indicates the escape of gas from de-

fective packing or gasket around the combustion chamber.

It will be noticed that the finger or hand *f* has a lug *m* on its back adapted to seat in a cavity or pocket *n* on the inside of the casing and to which said lug is retired by 70 the spring *s* when the finger is turned upright out of use. From this point the finger can be rotated in either direction but preferably is swept over the contacts in the order of their numbers. A relatively deep 75 casing *C* is preferred to house finger *f* and the contacts *g* sufficiently to place them in a dark zone or area for a better display of the jump-sparks, and the openings *o* are made relatively small for the same reason. 80

What I claim is:

1. A trouble detector for internal-combustion engines, comprising a casing and a series of electrical terminals therein, a finger provided with a stem slideable and rotatable 85 in said casing and said finger adapted to be brought into spark-producing relations with said terminals and to be retired therefrom.

2. A trouble detector for internal-combustion engines, comprising a series of contact 90 points arranged in a circle, a spark-producing finger rotatable over said points provided with a stem, a casing in which said stem is rotatable and slideable, and a spring adapted to retract the finger after use. 95

3. In combination, a casing, a diaphragm therein and a series of contact points about a common center thereon, a multiple cylinder engine having electrical ignition devices corresponding to said contact points and 100 wires electrically connecting said points and devices, ground connections for the casing and said devices, and a short-circuiting finger rotatably and depressibly mounted opposite said contact points and exposed to observation through said casing. 105

4. A trouble detector as described comprising a casing having a series of observation openings in its front and a dial on said front having designating marks corresponding to said openings, a finger having an arbor rotatably and slidably mounted in said casing and exposed through said openings, and a spring mounted on said arbor to retract said finger. 110

5. A trouble detector as described having a casing and an insulating plate therein provided with short-circuiting contact points in a circle thereon, the said plate being spaced and retired from the front of said 120 casing, a finger in said space adapted to be rotated into current-detecting relations with said contact points, a rotatable arbor for said finger slidably mounted in said casing, and a spring adapted to retire and maintain 125 said finger in a retired position relatively to said contact points.

6. A trouble detector for multiple cylinder

explosive engines, comprising a casing having a dial face with a cavity on the inside thereof, a depressible finger behind said face provided with a projection adapted to enter 5 said cavity, an arbor carrying said finger, a spring about said arbor adapted to hold said projection in said casing, and an insulating base plate having a series of elec-

trical terminals arranged in a circle thereon opposite said finger.

In testimony whereof I affix my signature in presence of two witnesses.

SAMUEL LAZARUS.
